CRISS-CROSS CURTAIN

Filed May 14, 1945

UNITED STATES PATENT OFFICE

2,410,662

CRISSCROSS CURTAIN

George Kahn, Lawrence, N. Y.

Application May 14, 1945, Serial No. 593,716

5 Claims. (Cl. 160—123)

1. The present invention is related to curtains and more particularly to a plurality of curtains whereby the same may be mounted on a single rod to give various decorative effects.

Curtains of the criss-cross type are well-known and have been used for a long time. Such curtains usually consist of two side curtains which are hung on a window so as to cross each other, and a third short curtain or ruffle on the top thereof. In hanging such curtains it was heretofore necessary to use two and sometimes three curtain rods on which each of the individual curtains were hung in order to give an overlapping effect. Such curtain rods are relatively expensive and it has become highly desirable to simplify the structure and to eliminate the plurality of rods. To accomplish this it has been proposed to sew together all three of the curtain elements into a single unit. Such a unit may be mounted on a single rod, but it suffers from a number of disadvantages. There is no flexibility in the curtain assembly and it is adapted to be fitted on to but a single size or type of window. Also, the laundering of such an assembly is quite difficult and unsatisfactory due to the overlapping layers of material and ruffles thereon which render it extremely difficult to properly press or iron the curtain structure.

The present invention is intended and adapted to overcome the difficulties and disadvantages inherent in prior curtain structures and to provide a plurality of curtain members which may be mounted on a single rod and which can be readily introduced or removed.

It is also among the objects of the present invention to provide a plurality of curtain members which are capable of being adapted to be hung in various styles and which are adapted for use on windows of varying sizes or widths.

It is further among the objects of the present invention to provide a curtain structure which may be readily and simply laundered and which presents no problems in ironing or pressing thereof.

It is still further among the objects of the present invention to provide a curtain structure which is simple and inexpensive, with simple means whereby the various elements may be threaded on to a single rod.

In practicing the present invention, there is provided a pair of curtains as usual, each of the curtains being adapted to be hung on a side of a window. Each curtain is provided along the upper edge thereof with a plurality of spaced loops sewed or otherwise secured thereto. There

is also provided a curtain ruffle or valance which is adapted to be extended across the window at the top thereof. The ruffle is provided along the back thereof with a plurality of spaced loops. In order to assemble the curtain, the several parts may be laid out in their final respective positions and then a curtain rod is threaded through the various loops on the three parts of the curtain. Then the rod may be mounted along the top of the window in suitable holders.

In the accompanying drawing constituting a part hereof and in which like reference characters indicate like parts,

Fig. 1 is a front elevational view of a set of curtains hung on a single rod in criss-cross style, some parts being broken away for clearness.

Fig. 2 is an enlarged fragmentary perspective rear view of that portion of the curtain assembly shown in Fig. 1 which is at the upper left-hand corner of said figure, the curtain and ruffle being shown in slightly offset relation.

Fig. 3 is a fragmentary front elevational view of the same curtain structure as shown in Fig. 1, but assembled on the rod in a different manner or style.

Fig. 4 is a perspective view of a piece of loop tape which may be sewed along the upper edge of the curtain members in place of individual loops, and

Fig. 5 is a perspective view of a piece of ladder tape which may be sewed on the rear face of the ruffle in place of individual loops.

With reference to Fig. 1, there is provided a side curtain 1 having a ruffle 2 along one vertical edge, the other edge 3 being plain and adjacent to the side edge of the window. A series of loops 4 in spaced relation are sewed along the upper edge of curtain 1. A similar curtain 5 is provided with a ruffle 6 along one vertical edge, the other vertical edge 7 being plain and being placed adjacent to the opposite side of the window. It is provided along this upper edge with a series of spaced loops 8 suitably attached to curtain 5.

45 The ordinary curtain rod 9 has loops 4 and 8 threaded thereon as shown in Fig. 1 with the loops on the overlapping portions of curtains 1 and 5 alternating in their assembly on rod 9. Tie backs 10 and 11 may be provided on curtains 1 and 5 respectively, as is well known.

The ruffle consists essentially of a band 12 having along its lower edge a ruffle 13 stitched thereto. On the rear face of band 12 is a series of spaced loops 14 sewed in place as shown in Fig. 2. The spacing of loops 4, 8 and 14 is pref-

erably the same in all of the curtain elements. Said ruffle 13 is threaded onto rod 9 at the same time as loops 4 and 8. This is accomplished by laying out curtains 1 and 5 on a suitable surface in their proper final positions and placing ruffle 13 thereon in its final position. Then rod 9 is threaded into each of the loops in their proper respective positions as shown in Fig. 1. This simple and complete assembly may then be mounted on a window.

The style of mounting as shown in Fig. 1 illustrates the flexibility of the present invention. In Fig. 2 the same curtains 1 and 5 and ruffle 13 are mounted on a single rod. In this case, instead of crossing over, each of curtains 1 and 5 is placed along a side of the window with a substantial space between said curtains. The ruffle is hung as in Fig. 1. This gives an entirely different effect than is given by the same curtains in Fig. 1.

In order to simplify the construction of the several curtains, particularly in that considerable labor is necessary to sew individual loop members to the several elements, there is provided a woven tape as shown in Fig. 4 to replace individual loops 4 and 8. The integrally woven tape consists of a band 15 and spaced loops 16 extending therefrom. This tape may be attached to curtains 1 and 5 by sewing band 15 along the upper edges thereof, thereby in a single sewing operation the entire group of loops is quickly sewed in place.

In Fig. 5 there is shown a fragment of a ladder tape which consists essentially of a pair of parallel bands 17 and 18 having spaced cross members 19 therebetween. All three elements are woven in a loom simultaneously to form a strong, simple and unitary structure. The ladder tape may replace loops 14 on ruffle 13. In order to sew the same in place the ladder tape is placed along the rear face of band 12 and two lines of stitching are formed on the side members 17 and 18, whereby cross members 19 form loops which are equivalent to loops 14 of Fig. 2.

It will be noted that the structure of the present invention is quite simple in that but very little sewing operations are necessary in order to form the same. The individual members of the curtain assembly may be hung in a variety of ways as illustrated in Figs. 1 and 3. It is also possible to utilize but a single curtain such as 1 or 5 on a window and having ruffle 13 mounted thereon. Other styles of hanging may also be adapted. Because of the provision of loops on the three elements, a single rod may be used to mount the same and the mounting may be changed or the curtains may be removed readily and simply with but little labor. Because of the provision of separate curtain elements, each of them may be readily laundered or cleaned and the ironing operation is quite simple because each of the members may be ironed separately.

Although I have described the invention setting forth a single embodiment thereof, it will be apparent to those skilled in the art that vari-

ous changes in the details of the practice of the invention may be made within the spirit thereof. The curtains may be made of any desired materials and the embellishments such as flanges 2 and 6 may be changed to other types of ornamentation or may be omitted. In place of the loops and tapes herein described, other elements giving equivalent results may be utilized. Various other changes may be made in the details of construction without departing from the spirit of the invention and therefore the invention is to be broadly construed and not to be limited except by the claims appended hereto.

I claim:

1. A curtain structure comprising a pair of curtains, each of said curtains having a plurality of spaced loops along the upper edge thereof, each curtain being adapted to cover a side of a window, a curtain ruffle adapted to be extended across said window, spaced loops on said ruffle, whereby said curtains and ruffle may be mounted on a single curtain rod in superposed positions by threading the several loops on said rod.

2. A curtain structure comprising a pair of curtains, each of said curtains having a plurality of spaced loops along the upper edge thereof, each curtain being adapted to cover a side of a window, a curtain ruffle adapted to be extended across said window, spaced loops on the rear face of said ruffle, whereby said curtains and ruffle may be mounted on a single curtain rod in superposed position by threading the several loops on said rod.

3. A curtain structure comprising a pair of curtains, each of said curtains having a plurality of spaced loops along the upper edge thereof, each curtain being adapted to cover a side of a window, a curtain ruffle adapted to be extended across said window, spaced loops on said ruffle, said curtains being overlapped, whereby said curtains and ruffle may be mounted on a single curtain rod in superposed position by threading the several loops on said rod.

4. A curtain structure comprising a pair of curtains, each of said curtains having a tape formed integrally with a plurality of spaced loops along the upper edge thereof, each curtain being adapted to cover a side of a window, a curtain ruffle adapted to be extended across said window, spaced loops on said ruffle, whereby said curtains and ruffle may be mounted on a single curtain rod in superposed position by threading the several loops on said rod.

5. A curtain structure comprising a pair of curtains, each of said curtains having a plurality of spaced loops along the upper edge thereof, each curtain being adapted to cover a side of a window, a curtain ruffle adapted to be extended across said window, a ladder tape secured along its sides on said ruffle, whereby said curtains and ruffle may be mounted on a single curtain rod in superposed position by threading the several loops on said rod.

GEORGE KAHN.
